[57] CLAIM

I claim the ornamental design for the kneeling disk, as shown and described.

DESCRIPTION

FIG. 1 is a perspective view of a kneeling disk;

FIG. 2 is a top view of the kneeling disk shown in FIG. 1;

FIG. 3 is a bottom view of the kneeling disk shown in FIG.

1;

FIG. 4 is a front view of the kneeling disk shown in FIG. 1;

FIG. 5 is a right side view of the kneeling disk shown in FIG.

1;

FIG. 6 is a back view of the kneeling disk shown in FIG. 1;

FIG. 7 is a left side view of the kneeling disk shown in FIG.

1;

FIG. 8 is a perspective of a second embodiment of a kneeling

disk;

FIG. 9 is a top view of the kneeling disk shown in FIG. 8;

FIG. 10 is a bottom view of the kneeling disk shown in FIG.

8;

FIG. 11 is a front view of the kneeling disk shown in FIG.

8;

FIG. 12 is a right side view of the kneeling disk shown in FIG.

8;

FIG. 13 is a back view of the kneeling disk shown in FIG.

8;

FIG. 14 is a left side view of the kneeling disk shown in FIG.

8.

The broken lines in FIGS. 1-14 showing portions of the

upper edge of the kneeling disk and portions of a soft

cushion are for illustrative purposes only and form no part

of the claimed design.
